United States Patent Office

Des. 182,010
Patented Jan. 28, 1958

182,010

ELECTRONIC CABINET

James G. Wells, Chicago, and Herbert C. Golz, Aurora,
Ill., assignors to Elgin Metalformers Corporation, Elgin,
Ill., a corporation of Illinois

Application May 25, 1956, Serial No. 41,647

Term of patent 14 years

(Cl. D26—5)

Fig. 1.

Fig. 2.

Fig. 1 is a perspective view of an electronic cabinet showing our new design; and

Fig. 2 is a side elevational view thereof.

The opposite side, not shown, has substantially the same appearance as the side shown and the back is conventional.

The dominant features of our new design are shown in solid lines in the drawings.

We claim:

The ornamental design for an electronic cabinet, substantially as shown and described.
